UNITED STATES PATENT OFFICE.

CHARLES BINZER, OF NEW YORK, N. Y.

DESIGN FOR A LAMP-SHADE.

Specification forming part of Design No. 5,320, dated October 24, 1871.

To all whom it may concern:

Be it known that I, CHARLES BINZER, of the city, county, and State of New York, have invented and produced a new and original Design for a Lamp-Shade, of which the following is a description:

The accompanying drawing is a side view of a lamp-shade made according to my design.

The shade consists of two frustums, *a* and *d*, of cones of different inclinations. The upper, *a*, of these frustums is of greater inclination than the lower, *d*, and has lozenge-shaped openings *b b* in it for pieces of transparent or translucent material. The edges of these openings are scal-

loped and perforated, as shown in the drawing. At the top edge of this upper portion is a slight bead, *c*. The lower frustum, *d*, of the shade has a bead, *e*, running round its middle, and its lower edge is scalloped, as represented in the drawing.

What I claim as my invention, and desire to secure by Letters Patent, is—

The design for a lamp-shade, substantially as described and represented in the drawing.

C. BINZER.
